UNITED STATES PATENT OFFICE.

ROY EDGAR HARDY, OF DETROIT, MICHIGAN, ASSIGNOR TO DETROIT MOTOR WORKS, OF DETROIT, MICHIGAN.

DESIGN FOR AN ENGINE FRAME OR CASING.

SPECIFICATION forming part of Design No. 35,623, dated January 28, 1902.

Application filed November 29, 1901. Serial No. 84,151. Term of patent 3½ years.

To all whom it may concern:

Be it known that I, ROY EDGAR HARDY, a citizen of the United States of America, residing at Detroit, in the county of Wayne and State 5 of Michigan, have invented and produced a new and original Design for an Engine Frame or Casing, of which the following is a specification, reference being had therein to the accompanying drawings, forming part thereof, 10 and in which—

Figure 1 is a side elevation of an engine frame or casing, showing my new design. Fig. 2 is a plan view thereof.

As shown in the drawings, the leading or 15 characteristic features of my design are the lower vertically-extended cylindrical portion A and the upper cylindrical portion C, of lesser diameter, connected by a curved portion which in cross-section has an ogee- 20 curved outline. The lower end of the portion A is curved outward slightly to meet an

outwardly-extended flange B or base portion, and the portion C is surmounted by a top or cap D, of slightly-greater diameter than the diameter of the portion C and having an upwardly-rounded top. On opposite sides of the curved portion which connects the portions A and C are outlined the escutcheons E by the fillets or ribs a, which project slightly from the surface of the casing. 25 30

Having described my invention, what I claim as new, and desire to secure by Letters Patent, is—

The design for an engine frame or casing, as herein shown and described. 35

In testimony whereof I affix my signature in presence of two witnesses.

ROY EDGAR HARDY.
